STRETCH-BENDING MACHINE WITH WORK CLAMPS MOUNTED ON PIVOTED ARMS

Ewalt A. Rathgen, Philadelphia, Pa., assignor to
 The Budd Company, Philadelphia, Pa., a corporation of Pennsylvania

Application December 2, 1944, Serial No. 566,375

2 Claims. (Cl. 153—32)

1

The invention relates to a stretch bending machine, that is, a machine which subjects a sheet or section simultaneously to bending and stretching forces so as to bring it permanently into a desired shape.

More particularly, the invention relates to a machine of the indicated type provided with two swingable arms each of which carries a vise for holding one end of the workpiece.

Among the objects of the invention is a stretch bending machine which permits production of shapes which are different on both sides of the longitudinal center of the workpiece.

Another object of the invention is a stretch bending machine which permits the convenient manufacture of shapes which are curved in more than one plane.

The objects of the invention are outstandingly achieved by a stretch bending machine having separate and independently controllable driving means for moving the two vises holding the ends of the workpiece.

Other objects, features and advantages of the invention will be more easily understood from the two embodiments which are illustrated in the attached drawing and described in the following:

In the drawing,

Figure 1 is a diagrammatic small-scale plan view of a stretch bending machine representing one embodiment of the invention;

Figure 2 is a fragmentary elevation of part of the machine shown in Figure 1 on a larger scale;

Figure 3 is a section substantially along line 3—3 of Figure 1 on the scale of Figure 2;

Figures 4 and 5 are fragmentary sections along the correspondingly numbered lines of Figure 1 on the scale of Figures 2 and 3;

Figure 6 is a fragmentary elevation view in the direction of the arrows 6—6 of Figure 1 on the scale of Figures 2 to 5;

Figure 7 is a small-scale plan view similar to Figure 1 yet of another embodiment of the invention;

Figure 8 is a fragmentary plan view of a central portion of the machine shown in Figure 7 on a considerably larger scale;

Figure 9 is an elevational view partly in section along line 9—9 of Figure 8;

Figure 10 is a vertical section substantially along line 10—10 of Figure 8;

Figure 11 is a fragmentary vertical section along line 11—11 of Figure 8;

Figure 12 is a fragmentary plan view of the portion of Figure 7 surrounded by the circle 10 yet on a considerably larger scale;

2

Figure 13 is a side elevation of Figure 12; and Figure 14 is a fragmentary section along line 14—14 of Figure 13.

In the embodiment illustrated in Figures 1 to 6, a base plate 20 is supported by and appropriately secured to the floor 21. Integrally secured to the base 20 near one end thereof is a vertical plate 22. Corner brackets 23 assist in holding plate 22 and base 20 in position. A plate structure 24 is guided movably along a vertical path by gibs 25 on the vertical marginal portions 26 of the plate 22. The underside of plate 24 is engaged by the rod 27 of a piston 28 movable in a vertical cylinder 29. The rod 27 extends through an opening in the base plate 20, and the cylinder 29 is arranged beneath the base. Admittance of a pressure medium to the cylinder 29 beneath the piston 28 will cause the plate 24 to move upwardly along plate 22.

20 A pair of brackets 30 are horizontally slidably supported by the plate 24 and by gibs 31 secured to plate 24. Each bracket 30 has two projecting portions 32, 33 carrying a vertical pin or shaft 34. The upper and lower sides of the projections 32, 33 of each bracket 30 are embraced by projections 35, 36 of an arm or cantilever structure 37. The shaft 34 extends into the projections 35, 36 so that each arm 37 may swivel about the axis of the respective shaft. Supported between the projections 32, 33 of each bracket 30 is the hub 38 of a large gear segment 39 which extends through a slot 40 of the respective arm 37 and which is attached by bolts 41 to a bracket 42 constituting an integral part of the vertically movable plate 24. The bolts 41 extend through horizontal slots 43 provided in said brackets 42. Upon loosening the bolts 41, each bracket 30 together with its arm 37 and gear segment 39 may be moved horizontally and then secured in any desired position by tightening the bolts.

The arm 37 has an elongated, plane, wide top 44, a vertical web 45 and a lower chord 46. Secured to the web 45 are an electric motor 46 and a speed reduction gear 47 driven by the motor and provided with a pinion 48 which engages the toothed outer circumference of the gear sector 39.

The motors are of the variable speed reversible type and each of them is controllable independently of the other by a controller 50.

50 Each arm 37 carries on its top plate 44 a horizontal cylinder 51 which may be secured in a great number of positions along the length of the arm by means of a bolt 52 extending through a hole provided in a bracket 53 supporting the motor and any one of a plurality of holes 52'

provided in the top plate 44 of the arm 37. The rod 54 of the piston 55 in the cylinder 51 has its outer end secured to a bracket 56 which is slidably guided by the top plate 44. Attached to the bracket 56 by universal joint connecting means 57 is a vise 58 adapted for holding one end of a workpiece 59.

Secured to the base 20 between the inner ends of the arms 37 is a support 60 for a table 61. The table has a raised margin 62 which in combination with the top surface of the table serves for holding a forming die 63. The die has one of its margins shaped in accordance with the form and the cross section of the workpiece 59, which in the embodiment is shown as an angle section.

Pressure medium may be admitted to the cylinders 29 and 51 by means of valves 64 and 65 and pipe lines 66, 67 and 68, 69. The pressure medium is supplied by a source (not shown) which feeds into the pipes 70, 71 leading to the valves 64, 65. 70', 71' are the exhaust or return pipes for the pressure medium.

The control means 50, 64, 65 are for the sake of simple diagrammatic illustration shown near the respective appertaining motors and cylinders but they will be arranged in reality, as a matter of course, together in one or two groups at a location or locations most suitable for the person or persons handling the production.

The operation of the machine will be evident to those skilled in the art from the foregoing description of the elements of the machine, so that a brief description of the operation will suffice.

After the die 63 has been placed on top of the table 61 and the cylinders 51 have been secured in place on the arms 37 at the distance from each other corresponding to the length of the workpiece, the latter is firmly secured in the vises 58. Hereafter pressure medium is admitted to the inner ends of the cylinders 51 by means of the valves 65 and pipes 68 so that the workpiece 59 is subjected to stretching. While the workpiece is in the stretched condition, the arms 37 are swung about their pivots 34 by means of the motors 46, the gears 47, the pinions 48 and the gear sectors 39, so that the workpiece is wrapped around the working edge of the die 63. During the movement of the arms, pressure in the cylinders 51 is maintained and, if need be, pressure medium admitted or partly released so as to maintain the desired stretching force which will cause the workpiece to assume permanently the exact form of the die surface yet without being stretched beyond its breaking point.

For other forms of the die different positions of the journals 34 for the arms are required. Such different positions can be easily attained by moving the brackets 30 along their gibs on the plate 24 after loosening the bolts 41 as described hereinbefore.

If the form of the die is not symmetric relative to the center plane 72 of the machine, asymmetrical positions for the journals 34 may be required and the two arms may have to move differently. The different movements of the arms can easily be achieved by the independent control and drive for the two arms, which was likewise described hereinbefore.

If the die is curved not only in plan view but also in vertical direction, then the vises have to be moved vertically relative to the die and its support. This vertical movement is achieved

by moving the plate 24 with the arms 37 and all other accessories, such as the vises 58, the cylinders 51, the motors 46, the gears 47 and the gear segments 39, vertically on the plate 22 by admitting pressure medium to the lower part of the cylinder 29 while the arms are simultaneously swung about their pivots by means of the motors 46.

The embodiment illustrated in Figures 7 to 14 differs from the first embodiment mainly in the means for swinging the arms about their pivots and in the means for moving the die and the vises relative to each other in vertical direction. This second embodiment shows certain details which may be incorporated also in the first embodiment, such as means for conveniently adjusting the position of the pivots for the arms, and such as a different type of universal joint connection between each vise and its piston rod.

The machine illustrated in Figures 7 to 14 has a large foundation plate 80 carrying at one end a cross member 81, at the other end a supporting structure 82 and near its middle a pedestal or bracket 83.

The structure 82 has a base plate 84, the inner end of which carries a columnar structure 85. Supported at a distance above the plate 84 by means of the columnar structure 85 is a horizontal beam structure composed of a lower plate 86 and an upper plate 87, vertical plates 88, 89, 90 and intervening horizontal plates 91, 92. The columnar structure is reinforced by an inclined member 93 extending between the plate 87 and the outer end of the plate 84. The entire structure 82 is composed, as will be evident from the drawing, of closed box sectional beams which give great strength and rigidity.

Gibs 94 are secured to the inner faces of the plates 89 and 90 and form with the latter a horizontal guide and support for a pair of brackets 95. A nut 96 secured to the bracket 95 is in engagement with a screw threaded shaft 97 rotatably but axially immovably supported in the structure 82 between the walls 91, 92. One nut 96 and one shaft 97 are provided on either side of the middle line (coinciding with section line 10—10 in Figure 8) of the machine for each of the brackets 95. One end of each shaft 97 projects beyond the outer end of the structure 82 and has a head 99 adapted for turning the shaft by means of a wrench, crank or the like.

Pivoted to each bracket 95 by means of a vertical pin 100 is the inner end of an arm 101. A gear segment 102 is secured by flanges and bolts or rivets 103 to the arm 101 near the lower edge thereof. The gear segment 102 has its periphery concentric to the respective pivot 100. The teeth of the gear segment 102 are engaged by a straight gear rack 104. The segment 102 and the rack 104 are held in engagement by a shoe 105 which has flanges 106 engaging a pathway concentric to the outer periphery of and provided on the segment 102. Each rack 104 is hitched by a coupling 107 to the rod 108 of a piston 109. The piston 109 is movable in a long cylinder 110 which has its outer end journalled at 111 to the cross beam 81. There is, of course, one cylinder, piston, piston rod, rack and gear segment for each of the two arms 101 as is shown in Figure 7.

Pressure medium can be admitted to or released from the interior of the cylinders 110 by the valves 112 and pipe lines 113, 114. Here again as in the first embodiment, the source of pressure medium is not shown but only the supply and exhaust or re-

turn lines 115, 115'. It should be noted that the movement of each arm is independently controllable by its valve 112.

The construction of the outer ends of the arms and of their top side is substantially the same as in the first embodiment; this goes also for the cylinders 116 for moving the vises 117 and the valves (not shown) for controlling the admittance of pressure medium to the cylinder independently from each other.

The universal joint connection between the piston rods 118 and the vises 117 is slightly different from the first embodiment. A bracket 119 is slidably guided on the top of each arm 101; this bracket carries by means of a ring 120 and intersecting vertical and horizontal pivots 121, 122 the inner end of the vise 117.

Secured to the central portion of the structure 82 between the brackets 95 is a member 123 which has formed therein an undercut vertical groove 124. Slidably guided in this groove 124 by a correspondingly shaped extension 125 is a member or structure 126. The opposite vertical edge 127 of this member is guided in a groove 128 provided on the previously mentioned bracket 83.

The structure 126 is in the form of a frame, the upper side of which is adapted for the attachment of a die or of a supporting table 129 by means of bolts extending into screw threaded holes 130. The table and its support are held in appropriate alignment by a ridge formed on the underside of the table entering a correspondingly shaped groove 129' on the top of the structure 126.

Secured to the underside of the top member and arranged within the opening surrounded by the four sides of the structure 126 is a hydraulic cylinder 133. The rod 134 of the piston in the cylinder 133 extends through an aperture in the bottom member of structure 126 and has its end secured to the foundation plate 80. Pressure medium may be admitted to the cylinder by means of the valve 135 from the pressure medium supply line 136 through the pipe line 137, 138; 139 is the return or exhaust pipe.

The operation of the machine shown in Figures 7 to 14 is substantially the same as that of the machine shown in Figures 1 to 6. After proper adjustment of the pivots 100 by moving the brackets 95 along the cross head of the structure 82, the adjustment of the cylinders 116 along their arms 101 and after having secured a die, such as indicated at 140, on the table 129, a workpiece indicated at 141 is secured in the vises 117. Hereafter pressure medium is admitted to the inner ends of the cylinders 116 and to the inner ends of the cylinders 119 with the effect that the workpiece is stretched and simultaneously the arms 101 with the workpiece are swung about their pivots 100. If the workpiece is curved in more than one plane, the die is moved relative to the vises holding the ends of the workpiece and relative to the machine as a whole in vertical direction by admitting pressure medium to the cylinder 133 so that the structure 126 with the table 129 and the die 140 is moved in vertical direction.

It will be understood that the invention is not restricted to the details of the two embodiments illustrated in the drawing and described here-

inbefore but that the invention is subject to such modifications and adaptations which are covered by the spirit and the language of the attached claims.

5 What is claimed is:

1. A stretch-bender comprising a base, a structure slidably guided on said base and provided with means for moving the structure back and forth, a pair of brackets supported by said structure slidably in a direction transversely to the direction of movement of said structure, said brackets each carrying an arm swingably about an axis which is about parallel to the axis of rotation of the other arm and about parallel to the direction of movement of said structure, means on said arms for gripping spaced portions of a workpiece and for stretching the latter between them, a forming die supported on said base, and power operated means for swinging said arms about their respective axes into relative positions in which a workpiece supported in stretched condition between them is brought against said forming die.
2. A stretch-bender comprising a base, a structure guided on said base for back and forth movement in one direction and means for imparting such movement to the structure, a pair of brackets supported by said structure slidably in a direction transversely to the direction of movement of the structure itself, said brackets each carrying an arm swingably about an axis which is about parallel to the direction of movement of said structure, means on said arms for gripping spaced portions of the workpiece and for stretching the latter between them, a forming die supported in stationary condition on said base in a position intersecting the line joining said gripping devices as said arms are swung about their respective axes.

40 EWALT A. RATHGEN.
